UNITED STATES PATENT OFFICE.

CLAYTON E. FREDERICKSON, OF CHICAGO, ILLINOIS, ASSIGNOR OF ONE-HALF TO GRACE C. STENGER, OF CHICAGO, ILLINOIS.

TWO-CYLINDER TWO-CYCLE INTERNAL-COMBUSTION ENGINE.

1,162,345.

Specification of Letters Patent. Patented Nov. 30, 1915.

Application filed March 30, 1914. Serial No. 828,289.

To all whom it may concern:

Be it known that I, CLAYTON E. FREDERICKSON, residing at Chicago, in the county of Cook and State of Illinois, have invented 5 certain new and useful Improvements in Two-Cylinder Two-Cycle Internal-Combustion Engines, of which the following is a specification.

My invention is a two cylinder two cycle cross port engine of the type wherein the compressed new charges formed in one cylinder pass into the working chamber of the other cylinder and the invention primarily has for its object to provide an internal combustion engine in which the parts are so arranged and designed as provided, first, for a full and effective cooling of the working cylinder and piston, second, for feeding into the working chambers unfoiled new charges, third, for the use of a looser piston without danger of fouling the new charges due to oil leaks or burnt mixtures passing the piston, and fourth, for the use of cooler new charges than can be formed by making the compression chamber in the working cylinder proper.

Again it is the object of the present invention to so design the engine as to embody simplicity and economy of manufacture while maintaining a relatively high degree of efficiency, and to provide an engine that is of light weight and has but few parts which are liable to become worn or injured or require replacement after long service.

With other objects in view which will be clear to those skilled in the art, the invention also resides in those novel details of construction, combination and arrangement of parts, all of which will be first fully described and then be specifically pointed out in the appended claims, reference being had to the accompanying drawings, in which:

Figure 1 is a side elevation and part vertical longitudinal section of the engine looking from the exhaust side. Fig. 2 is a vertical longitudinal section on the line 2—2 of Fig. 1. Fig. 3 is a detail side elevation of the engine, showing the arrangement of the intake manifold. Figs. 4 and 5 are diagrammatic views of the engine showing the operation of same.

Referring now to the drawings, in which like numerals of reference indicate like parts in all of the figures, 1 represents the crank

case and engine bed the same having a man-hole cover 3 on the bottom over the opening 2 and adapted to contain oil which is splashed by the spoon 24 to the moving parts within the crank case chamber.

The crank case is provided with two cylinder holes 6 to receive the pumping cylinder sections 4, whose flanges 5 rest on the crank case 1. The upper end of each cylinder section 4 is shouldered as at 7 to form a seat for the lower ends of the working cylinders 25, and the upper ends of the pumping cylinder sections 4 are provided with a transverse partition 8 and a bearing neck 9 to contain the packing 11 through which the piston rod 15 passes, a suitable cap 10 being provided as indicated for retaining the packing in place.

12 is the pumping piston which is provided with suitable rings 13 and with a central dome like portion 14, the upper end of which is closed by the screw plug 16 and flange 17 of the piston rod 15.

18 is the pin carried by the plug 16 on which the connecting rod 19 is mounted the connecting rod 19 having a split bearing 23 to engage the crank 22 of the crank shaft 20 and the cap of the split bearing 23 carries the spoon 24.

The working cylinders 25 each are provided with cooling fins 26 that embrace the cylinder from end to end and over the head, the head containing the compression space 27 as usual.

The working cylinder 25 is divided into two chambers by the working piston 52 the upper chamber being the working chamber, and the lower chamber the cooling or air chamber.

28 and 48 designate the piston controlled inlet and exhaust ports respectively of the working cylinder. The working cylinder is also provided near its lower end with a set of air ports 58 serving as vents for the air or cooling chamber.

The pumping cylinder sections 4 are provided with inlet ports 40 and outlet ports 31, the ports 31 leading into the ducts which connect the said ports with the inlet ports 28 of the opposite working cylinders. The ducts 29 have their entrant ends provided with a chamber 32 having a valved passage formed by the valve seat 37 and valve 33, the seat 37 being removable through the covered opening 39 as is also the valve 33 and its

spring 36, the valve 33 being a check valve and having its stem 34 slidable in the socket 35. The chamber 30 of the valved entrance of the duct delivers through the duct 29 into the inlet port 28 of the opposite working cylinder 25.

The inlet ducts 40 of the pump cylinder sections 4 deliver into a valve chamber 41 that is provided with a valve seat 42 and check valve 43 the stem 44 of the valve 43 being slidable in the socket 45, while the valve is pressed by the spring 46, to its seating position. The intake manifold, from the carburetor, is coupled to the casings 41 as clearly indicated in the drawings.

Each working cylinder 25 is formed with an exhaust duct 49 the several exhaust ducts, if desired, being designed for coupling with a suitable exhaust manifold as shown. Each working cylinder 25 has a threaded bore 50 for the reception of the spark plug 51.

The piston 52 is of the hollow type and provided with suitable packing rings 54 and a baffle 53 adjacent to the inlet port side 25 of the cylinder. The rod 15 is projected through a bore 55 and secured against rotation with relation to the piston 52 by a key 56 and nut 57.

The crank shaft 20 is mounted in suitable bearings 21 and is provided with the usual fly wheel 60 and the cylinder sections 25 and 4 are bolted together into the crank case by bolts 59 best shown in Fig. 1 of the drawings.

In operation on the down stroke of the pistons the air from the air chamber of the cylinder 25 is expelled through openings 58 and a new charge is drawn into the pumping chamber above the piston 12 from the intake manifold. On the up stroke of the pistons the charge of working agent above the piston 12 is being put under its initial compression and forced into the duct 29 so that as soon as the port 28 of the piston cylinder 25 is open this initially compressed mixture will be forced into the working chamber of the opposite cylinder to expel the old charge and re-charge the cylinder. While the new charge is being compressed above the piston 12 a new charge that has been pumped into the working cylinder 25 above that piston is being compressed by the piston 52 to its final compression. When the parts arrive at the position indicated in Fig. 2 the charge in the compression space 27 will be ignited to impel the piston 52 on its down stroke and consequently impel the other parts that move therewith. On the up stroke of the piston 52 air is drawn into the ports 58 to cool the piston and the working cylinder 25 and also the bearing for the piston rod 15. In the manner described, an effective cooling of the piston and working cylinder is obtained and also the cooling of the piston rod bearing.

I also call attention to the fact that in the present design the diameter of the pump cylinder 4 is made slightly greater than that of the working cylinder whereby to insure an ample charge of fresh working agent being pumped into the working chamber of the engine.

Any approved ignition system may be employed and any approved lubricating system for lubricating the working piston and I have therefore not specifically disclosed any such lubricating means.

From the foregoing description taken in connection with the accompanying drawings, it is thought the complete construction, operation and many advantages of my invention will be readily understood by those skilled in the art to which the invention appertains.

What I claim is:—

1. In a two cylinder two cycle engine, a crank case, a crank shaft, a pair of pumping cylinders mounted on the crank case, pistons operating in said cylinders, connecting rods between said crank shaft and said pistons, working cylinders mounted on said pumping cylinders, working pistons in said working cylinders and dividing each of the same into a working chamber and a cooling chamber, said working cylinder having air vents in communication with the cooling chamber, connections between the working pistons and their respective pump pistons, said cylinders each having intake and exhaust ports, an intake manifold communicating with the intake ports of the pumping cylinders, and cross-port ducts between the exhaust ports of the pumping cylinders and the intake ports of the working cylinders.

2. In an internal combustion engine of the type stated, a crank case, a crank shaft mounted therein, said crank case having cylinder receiving bores, flanged pumping cylinders set into said bores, said cylinders being open at the crank case ends and having closure webs and bearings at their outer ends, separate working cylinders set on and supported over the closed ends of said pumping cylinders in axial alignment with the same, means for cooling said working cylinders, said cooling means including heat radiating elements and air ports for admitting air into said working cylinders beneath the working pistons, pumping pistons in said pumping cylinders, working pistons in said working cylinders, piston rods connecting said pistons, and passing through said web bearings, connecting rods between said crank shaft and said pumping pistons, said pumping cylinders having inlet and outlet ports, said working cylinders having inlet and exhaust ports, cross-ducts connecting the outlet ports of said pumping cylinders and the intake ports of said working cylinders.

3. In an internal combustion engine of the

type stated, a crank case, a crank shaft mounted therein, said crank case having cylinder receiving bores, flanged pumping cylinders set into said bores, said cylinders being open at the crank case ends and having closure webs and bearings at their outer ends, working cylinders set on the closed ends of said pumping cylinders in axial alinement with the same, pumping pistons in said pumping cylinders, working pistons in said working cylinders, piston rods connecting said pistons, and passing through said web bearings, connecting rods between said crank shaft and said pumping pistons, 5 said pumping cylinders having inlet and outlet ports, said working cylinders having inlet and exhaust ports, cross-ducts connecting the outlet ports of said pumping cylinders and the intake ports of said working cylinders, each of said ducts including a valve chamber and a back check valve in said chamber, means for cooling said working cylinders, said cooling means including heat disbursing elements and air ports for 10 admitting air into the cylinders beneath the working pistons.

4. In an internal combustion engine of the type stated, a crank case, a crank shaft mounted therein, said crank case having cylinder receiving bores, flanged pumping cylinders set into said bores, said cylinders being open at the crank case ends and having closure webs and bearings at their outer ends, working cylinders set on the closed 15 ends of said pumping cylinders in axial alinement with the same, pumping pistons in said pumping cylinders, working pistons in said working cylinders, piston rods connecting said pistons, and passing through said web bearings, connecting rods between said crank shaft and said pumping pistons, 20 said pumping cylinders having inlet and outlet ports, said working cylinders having inlet and exhaust ports, cross-ducts connecting the outlet ports of said pumping cylinders and the intake ports of said working cylinders, each of said ducts including a valve chamber and a back check valve in said chamber, said working pistons dividing the respective cylinders into two chambers one of which forms the working chamber, and the other forms an air chamber, said 25 working cylinders having air vents for said air chambers and cooling fins on said working cylinder around both of the chambers thereof.

6. In an internal combustion engine of the type stated, a crank case, a crank shaft mounted therein, said crank case having cylinder receiving bores, flanged pumping cylinders set into said bores, said cylinders being open at the crank case ends and having closure webs and bearings at their outer 30 ends, working cylinders set on the closed ends of said pumping cylinders in axial alinement with the same, pumping pistons in said pumping cylinders, working pistons in said working cylinders, piston rods connecting said pistons, and passing through said web bearings, connecting rods between said crank shaft and said pumping pistons, 35 said pumping cylinders having inlet and outlet ports, said working cylinders having inlet and exhaust ports, cross-ducts connecting the outlet ports of said pumping cylinders and the intake ports of said working cylinders, each of said ducts including a valve chamber and a back check valve in said chamber, said working pistons dividing the respective cylinders into two chambers, one of which forms the working chamber and the other forms an air chamber, said working cylinder having air vents for said air chambers.

5. In an internal combustion engine of the type stated, a crank case, a crank shaft mounted therein, said crank case having cylinder

receiving bores, flanged pumping cylinders set into said bores, said cylinders being open at the crank case ends and having closure webs and bearings at their outer ends, working cylinders set on the closed ends of said pumping cylinders in axial alinement with the same, pumping pistons in said pumping cylinders, working pistons in said working cylinders, piston rods connecting said pistons, and passing through said web bearings, connecting rods between said crank shaft and said pumping pistons, 40 said pumping cylinders having inlet and outlet ports, said working cylinders having inlet and exhaust ports, cross-ducts connecting the outlet ports of said pumping cylinders and the intake ports of said working cylinders, each of said ducts including a valve chamber and a back check valve in said chamber, said working pistons dividing the respective cylinders into two chambers one of which forms the working chamber, and the other forms an air chamber, said 45 working cylinders having air vents for said air chambers and cooling fins on said working cylinder around both of the chambers thereof.

6. In an internal combustion engine of the type stated, a crank case, a crank shaft mounted therein, said crank case having cylinder receiving bores, flanged pumping cylinders set into said bores, said cylinders being open at the crank case ends and having closure webs and bearings at their outer ends, working cylinders set on the closed 50 ends of said pumping cylinders in axial alinement with the same, pumping pistons in said pumping cylinders, working pistons in said working cylinders, piston rods connecting said pistons, and passing through said web bearings, connecting rods between said crank shaft and said pumping pistons, 55 said pumping cylinders having inlet and outlet ports, said working cylinders having inlet and exhaust ports, cross-ducts connecting the outlet ports of said pumping cylinders and the intake ports of said working cylinders, said working pistons dividing the respective cylinders into two chambers, one of which forms the working chamber and the other forms an air chamber, said working cylinder having air vents for said air chambers.
